UNITED STATES PATENT OFFICE.

JOHN GEORGE AULSEBROOK KITCHEN, OF LANCASTER, AND ISAAC HENRY STOREY,
OF AMBLESIDE, ENGLAND.

MEANS FOR REVERSING SCREW-PROPELLED BOATS.

1,186,210.

Specification of Letters Patent.

Patented June 6, 1916.

Application filed October 28, 1914, Serial No. 869,051. Renewed May 3, 1916. Serial No. 95,290.

To all whom it may concern:

Be it known that we, JOHN GEORGE AULSEBROOK KITCHEN and ISAAC HENRY STOREY, subjects of the King of Great Britain and 5 Ireland, and residing at 7 Rose Bank, Scotforth, Lancaster, Lancaster county, England, and Loughrigg Brow, Ambleside, Westmoreland county, England, respectively, have invented certain new and useful Improvements 10 in Means for Reversing Screw-Propelled Boats, of which the following is a specification.

This invention relates to improvements in controlling and reversing the direction of 15 screw propelled boats by means of twin rudders specially mounted and operated, without reducing the speed of or reversing the propeller or propellers.

Now according to our invention, in place 20 of the twin flat rudders hitherto proposed, we use longitudinally channeled deflectors in pairs, which may be also used as rudders, independently mounted abreast of the propeller or propellers on vertically arranged 25 rotatable shafts, the hollow faces of the deflectors being opposite one another. The deflectors are totally submerged and transversely inclose the propeller or propellers as nearly as possible but without interfering 30 with the independent and necessary angular movement of either one of the pair, the rear ends of the deflectors being beveled so that when they are both deflected stern-ward to their full extent an inclosed hollow abut- 35 ment is formed behind each propeller. Normally the deflectors lie parallel with the keel and when they are to be used as rudders they can be moved to one side or the other, still remaining parallel. When however the de- 40 flectors are both turned so that their rear edges approach or touch one another, the mass of water thrust stern-ward by the propeller or propellers when rotating, is deflect- 45 ed in a forward direction in an efficient manner, and the boat will then proceed stern-ward. By symmetrically varying the relative angles of these deflectors while they remain with their faces longitudinally converging stern-ward, so that there is a larger 50 or smaller opening between the rear edges thereof, the speed can be varied both forward and stern-ward as the forward propelling effect of the screw or screws is only partially neutralized. By relatively varying 55 the angles of the deflectors while their rear

edges are in contact or nearly so, so that the two deflectors have different angles in relation to the keel, the boat can be steered by the deflectors while proceeding stern-ward.

The deflectors are provided with suitable 60 operating gear by which they can be moved, in either direction while remaining parallel with one another, so as to act as rudders, or in opposition to one another so as to provide the necessary abutment for reversing. 65

The twin flat rudders hitherto proposed could be set to form an abutment in one plane behind the propeller, or in two planes inclined laterally toward the propeller behind whereby the re-action of the column of 70 water thrust stern-ward by the propeller, was inefficient owing to the tendency of the column to spread out laterally at its base.

With our improvements, the utmost efficiency possible is obtained as practically no 75 water escapes in a radial direction when the deflectors are closed, the re-action being as desired. And further, the deflectors offer the least possible resistance when going astern, as well as when being used as rudders. 80

The drawings attached hereunto illustrate several applications of our invention to boats provided with a single propeller and with twin propellers. 85

Figure 1 represents the stern part of a boat in side elevation and Fig. 2 the same in end elevation. In these two views the plates forming the abutment and herein-after termed "deflectors" are intended to 90 act also as a rudder. Fig. 3 represents the deflectors in plan. Figs. 4 and 5 represent end elevation and plan respectively of the deflectors fixed for driving astern. Figs. 3 and 7 are similar views of the deflectors 95 being used as a rudder. Fig. 8 shows the deflectors in plan set for steering in one direction as the boat is being driven stern-ward. Fig. 9 represents in plan looking from underneath, the stern part of a boat 100 fitted with twin propellers, and Fig. 10 a side elevation of the same, with our improvements applied. Fig. 11 represents a diagrammatic view in plan of an arrangement for controlling the deflectors in a 105 simple manner.

Figs. 1 to 8 will first be referred to. In the example thereby illustrated, the ordinary rudder is dispensed with. The abutment is made (as hitherto stated) of con- 110

cave plates which are quite suitable to do duty as a rudder. There are thus in this case, two rudders which remain in parallel relationship for steering purposes while the boat is being driven forward, and act exactly in the same manner as a single rudder, if properly controlled, as they should move together. In the drawings, S represents the stern part of a boat to which our invention is applied, and P represents the propeller. The abutment consists of the deflector d and the deflector d^1 , the deflector d being fixed to the end of the vertical tubular shaft e and the deflector d^1 , to the end of the central shaft f . These shafts are concentrically arranged and pass through the stern part of the boat being mounted in suitable bearings therein. It will be seen that the two deflectors d and d^1 are exactly alike except that the foot h of the shaft e is fixed on the outside of the deflector d and the foot h^1 of the shaft f is fixed on the inside of the deflector d^1 . To the upper ends of the shafts are fixed lever arms such as g and g^1 to which the hand controlling gear is connected. Each deflector shown consists of an approximately semi-cylindrical shell with the corners at the front end rounded off as at 1 and at the rear end mitered as at 2. The hollow sides of the two deflectors face one another directly, the propeller being between. The lower part of each deflector is shown supported in a footstep bearing 3 carried by an arm 4 fixed to the keel of the boat. In Figs. 1 and 2, the two deflectors are parallel with the keel and in this position, the boat can be driven forward in a straight line. If the two deflectors d and d^1 are turned together so that they remain relatively parallel, either to the right hand or to the left, they will act in the same way as an ordinary rudder would do and the boat can easily be steered thereby. Figs. 6 and 7 show the deflectors d and d^1 turned to the right as they would be when used for steering forward in one direction. Figs. 4 and 5 show the deflectors d and d^1 , closed at their rear ends, the latter forming a mitered joint. In this position the boat will be driven sternward when the propeller is rotated for forward driving. The maximum speed sternward will be obtained when the two deflectors touch one another as shown in Figs. 4 and 5. If the rear edges 2 do not close, then the speed sternward will be reduced according to the width of opening there is between them. As long as the rear edges 2 of the deflectors are the same distance apart from the center line o of the keel O and the greater part of the propeller stream is deflected, the boat should move in a straight line sternward. If the opening between the edges 2 of the deflectors as their longitudinal surfaces converge, is not central with the keel but more to one side or

the other, or if the two edges 2 meet at one side or the other of the center line of the keel, the boat will be driven sternward in one direction or the other. Fig. 8 illustrates how the boat may be steered while being driven sternward by turning the deflectors d and d^1 so that their edges 2 meet or nearly meet at one side or the other of the center line o of the keel O . In this case the forward thrust of the re-directed mass of water driven against the deflectors d and d^1 , is not parallel with the keel and will tend to turn the boat around.

Fig. 9 represents in plan, looking from underneath, the stern part of a boat fitted with twin-propellers and deflectors arranged in accordance with our invention.

Fig. 10 represents a side elevation of the stern part of the boat. The deflectors d and d^1 are pivoted in footstep bearings at r , see Fig. 10. In this example also the deflectors act as rudders. Their edges 2 close against the keel O when the boat is being driven sternward. In order to enable the boat to be steered while moving sternward, one of the members is not allowed to close in contact with the keel at its rear end, whereby the tendency to travel in a straight line is modified by the unequal thrust of water on the two deflectors. Generally the remarks referring to Figs. 4 to 8 as to the relative positions of the deflectors for driving sternward, illustrated by Figs. 9 and 10, and for steering both forward and sternward, apply equally to the example shown in these views.

Fig. 11 shows in plan diagrammatically, a simple arrangement for controlling the movements of the deflectors by means of hand levers. This arrangement would necessitate the use of both hands, but in actual practice, a more convenient method would probably be used. It will be seen that the shaft e is provided with a lever arm g and the shaft f , with a similar arm g^1 fixed thereto. Within reach of the steersman are two hand levers g^2 and g^3 one on each side. These are connected with the lever arms g and g^1 by means of the coupling rods g^4 and g^5 . With this arrangement the positions of the two members of the deflectors can be varied at will so as to enable the boat to be steered in a forward direction by moving the hand levers to one side or the other in a parallel manner, or to cause the boat to move sternward by moving the levers away from one another, thereby masking the propeller behind. If the levers are moved so as to close together the two members of the abutment, the boat will travel directly sternward, but if the lever handles are pushed apart unevenly so that the deflectors assume a position similar to that shown in Fig. 8, the boat will move sternward in a curve to one side or the other according

to which side of the center line the deflectors miter or tend to miter. The deflectors are shown in the drawings provided with foot-step bearings but these may be discarded 5 where practicable.

In all the arrangements illustrated, the deflectors act as the rudder. It is obvious however that the ordinary rudder may be retained and used for steering while the boat 10 is being driven forward or sternward. In this case, the deflectors would remain parallel with the keel while the boat is progressing forward. If the ordinary rudder be retained the control of the deflectors for 15 reversing would perhaps be simplified as when the deflectors are to be used as rudders also, there must be a combined or differential arrangement for controlling the deflectors as such and as rudders actuated by one pair 20 of hands.

In the case of boats with three or more propellers, the deflectors may be arranged so that each propeller has one at each side as in Figs. 1 and 2. In cases where this 25 course is practicable, deflectors arranged as shown in Figs. 9 and 10 may be used where there are four propellers. Or the sternmost pair may have deflectors so arranged, and the forward outer pair of propellers, deflectors arranged as described with reference 30 to Figs. 1 and 2.

In the adjustment shown in Fig. 3, the abutments d and d' are disposed endwise in the water with their edges facing the current and with their larger areas parallel with the current thereby reducing resistance to a minimum. This adjustment we will term a feathering adjustment. In Fig. 7, the abutments are adjusted in a partially 40 feathering position wherein the greater areas of their lateral faces offer resistance to the water to swerve the boat from a straight line course.

We claim:—

45 1. A ship provided with a propeller, a reversing and controlling means comprising a hollow body, and means for adjusting said body into a feathering or partially feathering position laterally of the propeller, or into a wake enveloping and arresting position behind said propeller, substantially as described.

50 2. A ship provided with a propeller, a reversing and controlling means comprising a hollow body mounted to swing about a substantially vertical axis intersecting the axis of rotation of the propeller, and means for adjusting said body into a feathering or partially feathering position laterally of the propeller, or into a wake enveloping and arresting position with respect to said propeller, substantially as and for the purpose set forth.

55 3. A ship provided with a propeller, a reversing and controlling means comprising a

substantially U-shaped body having its ends mounted for turning movement of said body about an axis substantially vertical and intersecting the axis of rotation of said propeller, and means for adjusting said body 70 into a full or partially feathering position or into a trailing wake arresting position with respect to said propeller, substantially as described.

4. A ship provided with a propeller, and 75 a controlling and reversing means comprising coacting channel-shaped bodies, and means for separating said bodies from each other into opposed and lateral relation with respect to the propeller and into feathering 80 or partially feathering positions in the water, or into engaged or slightly spaced coacting relation behind and in the wake of the propeller to thereby form a hollow wake enveloping abutment, substantially as described. 85

5. A ship provided with a propeller, a controlling and reversing means comprising coacting channel-shaped bodies mounted to be rotated about a vertical axis intersecting 90 the axis of rotation of the propeller, and means for separating said bodies from each other into opposed lateral relation with respect to said propeller and into feathering 95 or partially feathering positions in the water, or into engaged coacting relation behind and in the wake of the propeller to thereby form a hollow wake enveloping abutment, substantially as described.

6. A ship provided with a propeller, 100 means comprising companion coacting hollow ship steering and reversing elements, and mechanism for bodily adjusting said elements into engaged coacting relation with respect to each other into an abrupt wake 105 abutting and enveloping relation behind the propeller or into angular positions with respect to the flow of the wake, substantially as described.

7. A ship provided with a propeller, a 110 steering and a reversing means comprising coacting companion channel members shaped to engage each other in edge to edge relation, and mechanism for adjusting said members into engaged or partially open relation with respect to each other and bodily adjusting said members in unison in either relation into an abrupt wake abutting relation behind the propeller or into angular positions with respect to the flow of the wake, 115 substantially as and for the purpose set forth.

8. A ship provided with a propeller, a steering and a reversing means comprising coacting companion channel members shaped to engage each other in edge to edge relation, to form a hollow body of miter formation, and means for adjusting said members in unison and in engaged relation with each other into an abrupt wake abutting relation 120 125

behind the propeller or into angular positions with respect to the flow of the wake, substantially as described.

9. A ship provided with a propeller, a hollow steering and reversing element having a concave portion and mounted to swing about a vertical axis intersecting the axis of said propeller with its concave portion facing the propeller, and means for adjusting said element with its hollow portion in the wake of and facing said propeller to reverse

the direction of the boat, or in angular positions on either side of the propeller to steer the boat, or in feathering lateral positions with respect to the propeller, substantially 15 as described.
